DESIGN FOR A STORE

Gordon L. Smith, Chattanooga, Tenn., assignor to The Kriptal Company, Chattanooga, Tenn., a corporation of Tennessee

Application July 13, 1936, Serial No. 63,828

Term of patent 14 years

To all whom it may concern:

Be it known that I, Gordon L. Smith, a citizen of the United States, residing at Chattanooga, Hamilton County, State of Tennessee, have invented a new, original, and ornamental Design for a Store, of which the following is a specification, reference being had to the accompanying drawing, forming part thereof.

Figure 1 is a perspective view of a store

showing my new design. Fig. 2 is a plan view of the store shown in perspective in Fig. 1. The side walls of the building invisible in Fig. 1 are plain in construction except for the provision of necessary doors or windows.

I claim:

The ornamental design for a store as shown and described.

GORDON L. SMITH.
